(57) **CLAIM**

The ornamental design for a two-piece bow tie, as shown and described.

DESCRIPTION

3.-4. Bow ties

Figure 3.1 is a front view of a two-piece bow tie showing the bow portion of the new design in an unfolded position.

Figure 3.2 is a perspective view thereof in a folded position; Figure 3.3 is a front view thereof showing the bow and tie in an alternate folded position; and

Figure 3.4 is a front perspective view thereof in an alternate folded position.

Figure 4.1 is a front view of a second embodiment of the two-piece bow tie showing the bow portion in an unfolded position;

Figure 4.2 is a perspective view thereof in a folded position; Figure 4.3 is a front view thereof showing the bow and tie in an alternate folded position; and

Figure 4.4 is a front perspective view thereof in an alternate folded position.

The broken lines in the figures are for the purpose of illustrating portions of the two-piece bow tie and form no part of the claim.
